FOUNTAIN TOOTHBRUSH

Frederick H. Borsini, Dayton, Ohio, assignor to
William H. McGhee, Dayton, Ohio

Application November 29, 1945, Serial No. 631,507

2 Claims. (Cl. 15—133)

1

This invention relates to a tooth brush and one object of the invention is to provide a tooth brush having a receptacle for liquid dentifrice from which the dentifrice may be drawn into the mouth of the user.

A further object of the invention is to provide such a tooth brush having a cylindrical brush head provided with an axial orifice through which the dentifrice may be drawn by suction.

A further object of the invention is to provide such a tooth brush which is tightly sealed against leakage when not in use.

A further object of the invention is to provide such a tooth brush of such size and shape that it may be carried upright in a pocket.

A further object of the invention is to provide a tooth brush having a cylindrical brush of soft rubber.

Other objects of the invention may appear as the tooth brush is described in detail.

In the accompanying drawings Fig. 1 is a section taken longitudinally of the brush with the cap in place; Fig. 2 is a longitudinal section, on an enlarged scale, taken through the brush head and its supporting element on the line 2—2 of Fig. 1; Fig. 3 is a transverse section taken on the line 3—3 of Fig. 1; Fig. 4 is an end elevation of the brush head; and Fig. 5 is an end elevation of the cap.

In these drawings I have illustrated a preferred embodiment of the invention but it is to be understood that the tooth brush as a whole, as well as the several parts thereof, may take various forms without departing from the spirit of the invention.

In the embodiment here illustrated, the tooth brush comprises a handle portion 6 having within the same a receptacle to contain dentifrice. Preferably the handle is tubular in form and is permanently closed at its outer end, the chamber 7 within the handle constituting a receptacle for liquid dentifrice. Connected with the inner end of the handle is a brush supporting element 8 which is detachably connected with the handle to form a closure therefor which can be readily removed for the purpose of filling or cleaning the chamber 7. In the present arrangement, the inner end of the tubular handle is provided with a screw thread 9 and the adjacent end of the supporting element is screw threaded, as shown at 10, to engage the thread in the handle, thus enabling the handle to be quickly and easily separated from the supporting element. The supporting element is provided adjacent the inner end of the screw threaded portion 10 with a part

5 of enlarged diameter forming a shoulder 11 adapted to engage the end of the tubular handle and to tightly seal the same when the supporting element is screwed into the handle. The forward or outer portion of the supporting element is so constructed as to support a brush head of the desired type and in the present instance it is adapted to extend into an opening in the brush head and is provided with a longitudinal passage or conduit 12 which extends for the full length thereof and communicates at its rear end with the chamber 7.

10 The brush head may be of any suitable type but it is preferably provided with a longitudinal opening 13 adapted to receive the supporting element and having at its outer or forward end an orifice communicating with the passage 12, the passage and orifice constituting a conduit extending the full length of the brush. It is also preferable that the brush head shall be cylindrical in form and that the end portion thereof in which the orifice is formed shall be of yieldable material. In the present instance the brush head, 14, is shown as formed of soft rubber and as comprising a tubular body portion 15 from which a multitude of small diameter projections 16 extend radially in all directions and constitute the bristles of the brush. The opening through this tubular body is closed at its forward end except for a small orifice 13. The length of the opening is such that when the supporting element is fully inserted therein its forward end will be close to or in contact with the closed end of the opening, and the orifice 13 will be in direct communication with the passage 12. That portion of the supporting element which engages the brush head is of an overall diameter slightly greater than the interior diameter of the tubular body and has its outer end slightly tapered to facilitate its entrance into the tubular body. Thus when the tubular body is pressed onto the supporting element, it firmly grips the latter and is retained thereon. However, it is usually preferable to provide the supporting element with serrations 17 so that the contraction of the tubular body about the supporting element will cause portions thereof to enter the spaces between the serrations and thus very firmly retain the brush head on the supporting element. The serrations are shown in an exaggerated form and are usually of such depth that the brush head can be removed by applying force thereto, thereby enabling a worn brush head to be removed and a new one substituted therefor without discarding the tooth brush as a whole. When the supporting

element has been inserted in the tubular body of the brush head the passage 12 thereof is in direct communication with the orifice 13 and by placing the end of the tubular body between the lips and sucking thereon the liquid dentifrice may be drawn into the mouth of the user in such quantities as may be desired, the brush then being utilized to apply the dentifrice to the teeth. The orifice 13 is of such small diameter that little or no dentifrice will escape therefrom while being so used. Preferably the outer end of the tubular body, in which the orifice is formed, is tapered, as shown more particularly in Fig. 2, and due to the resiliency of the rubber it constitutes a nipple which facilitates the drawing of successive small portions of the dentifrice into the mouth of the user.

The tooth brush is provided with a cap 18 to enclose the brush head and to protect the same when the brush is not in use. As here shown, the cap 18 is cylindrical in form, is closed at its outer end and has its inner end of such internal diameter that it may be pressed over the inner end of the handle 6 and will be retained thereon by friction. While the orifice 13 is so small that there will be little leakage of the liquid through the same it is nevertheless desirable that means be provided to positively prevent leakage and the cap 18 is provided with a member adapted to seal the orifice. This member is here shown as a tapered plug or valve 19 arranged within and secured to the end wall of the cap in such a position that the small end thereof will enter the orifice when the cap is placed on the brush. Due to the resiliency of the rubber in which the orifice is formed, a very tight seal is thus provided. The sealing member or valve 19 may be secured to the cap in any suitable manner as by an attaching member 20 which is here shown as rigidly secured to, and preferably formed integral with, the sealing member and which extends through end wall of the cap, and has its outer end upset or riveted.

As will be noted the tooth brush has much the form and external appearance of a fountain pen and is adapted to be carried in a vest pocket in an upright position. For the purpose of retaining the tooth brush in the pocket the cap is provided with a clip 21 extending lengthwise thereof and this clip has an end portion 22 extending across the outer end of the cap and provided with an opening through which the end of the attaching member 20 may be inserted before it is riveted, so that the one attaching member serves to connect both the clip and the sealing member with the cap.

The tooth brush, with the exception of the brush head, may be formed of any suitable material, such as a suitable plastic, and by making it of transparent material the contents of the chamber 7 are at all times visible, so that the amount of dentifrice contained therein can be easily ascertained. The body portion of the brush head is preferably formed of yieldable material, such as soft rubber, which will tightly grip the supporting element but can be easily removed therefrom. The bristles, or brushing

elements, may be of soft rubber, as shown, or of any suitable material.

While I have shown and described one embodiment of my invention I wish it to be understood that I do not desire to be limited to the details thereof as various modifications may occur to a person skilled in the art.

Having now fully described what I claim as new and desire to secure by Letters Patent, is:

1. In a tooth brush, a handle having therein a chamber to receive a fluid dentifrice, an elongate member connected at one end with said handle and having therein a longitudinal passage open at its ends only, and communicating at its inner end with said chamber, said elongate member being provided with outwardly directed serrations, a cylindrical brush head separate from and mounted on said elongate member and having an end portion extending beyond the outer end of said elongate member, said cylindrical brush head being made of resilient material resiliently engaging the serrations on the elongate member to hold the brush head in position, said brush head having resilient bristles extending radially from all sides thereof, said end portion of said brush head having a restricted orifice communicating with the outer end of said passage in said elongate member and constituting a mouth piece through which dentifrice may be drawn from said passage.
2. In a tooth brush, a handle having therein a chamber to receive a fluid dentifrice, an elongate member connected at one end with said handle and having therein a longitudinal passage open at its ends only, and communicating at its inner end with said chamber, a cylindrical brush head of resilient material mounted about and having firm contact with said elongate member, resilient bristles extending radially from all sides of said cylindrical head, said brush head having an outer end wall substantially in contact with the outer end of said elongate member, said end wall having a restricted orifice in line with and communicating with the open outer end of the passage in said elongate member, said end wall being of substantial thickness and having an outwardly tapered exterior surface.

FREDERICK H. BORSINI.
